Patented Dec. 15, 1914.

UNITED STATES PATENT OFFICE.

WILLIAM A. MILLER, OF MOUNTAIN HOME, IDAHO.

HAY-SWEEP.

1,121,389.

Specification of Letters Patent. Patented Dec. 15, 1914.

Application filed March 1, 1913. Serial No. 751,576.

To all whom it may concern:

Be it known that I, WILLIAM A. MILLER, a citizen of the United States, and a resident of Mountain Home, in the county of Elmore and State of Idaho, have invented a new and useful Improvement in Hay-Sweeps, of which the following is a specification.

My invention is an improvement in that class of so-called hay sweeps in which a pusher or hay-discharger is mounted slidably thereon and adapted for ejecting a load of hay from the sweep upon the arrival of the latter at a stack.

The details of construction, arrangement, and operation of parts are as hereinafter described, and illustrated in the accompanying drawing, which gives a perspective view of my improved sweep.

In the following description, lower-case letters are used to indicate the frame of the sweep, and numerals to indicate the slideable pusher, or hay-discharger, and its attachments.

The skeleton body or main frame of the sweep is rectangular and oblong in form, and constructed of upper and lower pairs of parallel boards *a*, *a'*, and transverse boards *b*, *b'*, these parts being securely nailed together. Thus constructed, the frame combines a high degree of rigidity and lightness. To the under side of the lower longitudinal bars *a'* are attached long teeth *c* which project forward of the frame as shown. Diagonal braces *d* are attached to some of these teeth and to the main frame proper, as shown. The said frame is supported upon running wheels *e*, which also constitute fulcra for the frame on which it may be tilted to adjust the ends of the teeth *c* nearer to, or farther from, the ground, as required to cause them to take up the hay in the most effective manner. Such tilting is effected by means of a connecting rod *f* and hand lever *g*, the latter being pivoted to the supplemental rear frame and provided with a toothed segment and pawl for locking it in any required position.

The supplemental frame comprises two long bars *h* which project rearwardly at a slight angle to each other, their front ends being hinged to the main frame and their rear ends supported upon pivoted wheels *i*. Transverse bars *j* and diagonal braces *j'* connect the lengthwise bars *h* thus assisting in forming a rigid frame. A driver's seat is attached to the rear portion of the supplemental frame.

The hay-pusher or discharger is formed of boards *1* connected by transverse boards *2* and a carrying frame composed of two thin but wide bars *3*, which are arranged parallel and whose rear ends are connected by a board *3^a*. The said bars *3* slide in contact with the outer sides of the middle transverse boards *b'* of the main frame. The rear portion *3^a* of the slideable pusher frame is connected with a hand lever *4* by means of a rod *5*, the said lever being pivoted to the cross bars *j* of the supplemental or rear frame. The bars *3* constitute the support for the pusher proper or discharge head *1* and slide upon the lower longitudinal bars *a'* of the main frame. In practical use of the sweep, horses or other draft animals are attached to it in a well known manner, and propel the sweep over the field, it being understood that the driver has first operated the lever *4* by pulling it backward so as to draw the pusher *1* back against the front edge of the main frame, thus leaving the front portions of the teeth *c* entirely exposed. When a load has been taken up by the teeth *c*, the sweep is propelled to the stack, and then the horses are backed so as to draw the apparatus backward while the driver at the same time pushes forward on the lever *4* so as to discharge the load from the teeth *c*.

I claim:

The improved hay-sweep comprising a main, wheeled, and toothed frame provided in its middle portion with transverse, parallel guide bars which serve also as means for connecting the front and rear portions of such frame, the pusher and the slideable

frame attached to it and supporting it slidably upon the main frame, and composed of parallel bars connected at their rear ends and working in contact with, and guided by, the aforesaid transverse bars of the main frame, and pivoted hand levers, and rods connecting the latter with the main frame

and pusher frame, for operating the rake frame and pusher, as described.

WILLIAM A. MILLER.
